(57) **CLAIM**

The ornamental design for a projector table with a graphical user interface, as shown and described.

DESCRIPTION

FIG. 1 is a front view of a first embodiment of a projector table with a graphical user interface showing our new design;

FIG. 2 is a second embodiment thereof;

FIG. 3 is a third embodiment thereof; and

FIG. 4 is a fourth embodiment thereof.

FIG. 5 is a fifth embodiment thereof;

FIG. 6 is a sixth embodiment thereof;

FIG. 7 is a seventh embodiment thereof; and

FIG. 8 is an eighth embodiment thereof.

FIG. 9 is a ninth embodiment thereof;

FIG. 10 is a tenth embodiment thereof;

FIG. 11 is an eleventh embodiment thereof; and

FIG. 12 is a twelfth embodiment thereof.

FIG. 13 is a thirteenth image thereof;

FIG. 14 is a fourteenth embodiment thereof;

FIG. 15 is a fifteenth embodiment thereof; and

FIG. 16 is a sixteenth embodiment thereof.

FIG. 17 is a seventeenth embodiment thereof;

FIG. 18 is an eighteenth embodiment thereof;

FIG. 19 is a nineteenth embodiment thereof; and

FIG. 20 is a twentieth image thereof.

FIG. 21 is a twenty-first embodiment thereof;

FIG. 22 is a twenty-second embodiment thereof;

FIG. 23 is a twenty-third embodiment thereof; and

FIG. 24 is a twenty-fourth embodiment thereof.

FIG. 25 is a twenty-fifth embodiment thereof;

FIG. 26 is a twenty-sixth embodiment thereof;

FIG. 27 is a twenty-seventh embodiment thereof; and,

FIG. 28 is a twenty-eighth embodiment thereof.

The outer most two-dot dot-dash lines of FIGS. 1-28 illustrate portions of the projector table and form no part of the claimed design. The inner single-dot dot-dash lines illustrate
